UNITED STATES PATENT OFFICE.

ANGELO ALBÉ, OF TURIN, ITALY.

TYPE-CASTING MACHINE.

1,352,644.

Specification of Letters Patent. Patented Sept. 14, 1920.

Application filed December 29, 1919. Serial No. 347,921.

To all whom it may concern:

Be it known that I, ANGELO ALBÉ, a subject of the King of Italy, and a resident of Turin, Italy, have invented certain new and useful Improvements in Type-Casting Machines, of which the following is a specification.

Type-casting machines, as usually constructed, comprise a part or mold providing the matrix of the desired type character and designed to close the orifice through which the molten metal is injected; and such mold must be located in a carefully-defined position with regard to stationary parts of the machine in order to cast the characters in correct position with relation to the edges or side faces of the type block. This is necessary in order to effect a true alinement and an even spacing of the characters relative to each other when used for printing.

Therefore, when a given type character is to be cast, the operator is required to adjust the position of the mold in two directions perpendicular to each other for the purpose of insuring the arrangement of the character at the same distance from the lower edge of the type block and at the proper distance from both side edges of the type block.

In the present practice, this operation is effected each time a given character is to be cast, and the correct position of the mold is only obtained experimentally; obviously such an operation is of long and difficult character, and requires careful attention on the part of the operator.

According to my invention, the drawbacks above referred to are removed, the mold holder being adapted to be adjusted in two directions perpendicular to each other by means of micrometer screws provided with graduations or verniers which give a true indication of the position of the holder and of the mold or matrix with relation to stationary parts of the machine.

In the accompanying drawings, which show by way of example one embodiment of the mold holder according to the invention, Figure 1 is a vertical section of the device along its longitudinal axis; Fig. 2 is a plan view thereof; Fig. 3 is a transverse section on line 3—3, Fig. 1; and Fig. 4 is a front view of the device.

As shown in said drawing, the device comprises a bracket 1 adapted to be secured on the casting machine at the place of the usual

mold holder; and on this bracket there is mounted for vertical sliding movement a support 2 which is connected therewith by means of a bolt 4 whose head 3 engages the bracket, the bolt being secured to said bracket and passing through a slot 5 formed in said support 2.

In the body of bracket 1 is journaled a vertical spindle 6 having a milled operating head 7 and a screw threaded portion 8, the latter engaging a nut 9 attached to support 2 by screws 28. The lower end of spindle 6 abuts against an adjusting screw 29 locked in position by a screw 30.

The spindle 6 may be rotated by manipulating head 7 for the purpose of adjusting vertically the support 2, the nut 9 attached to said support being operated by the screw-threaded portion 8 of said spindle. By giving the proper pitch to said screw 8 (say, a pitch of one millimeter) and by providing suitable vernier scales on adjacent stationary and movable parts of the device (for instance, on a flange 7' formed integral with head 7 and on a sleeve 1' integral with the bracket 1, or on an edge of the support and on the adjacent edge of the bracket 1) it is always possible to take an accurate reading of the indications defining the correct position of the support in the vertical direction, the said scales being preferably graduated in hundredths of a millimeter.

The indications which have been found by attempts in the described manner in connection with a given type character are suitably recorded, and then the device may be easily and truly adjusted at any time for casting the same character with even side spaces, the character being arranged, as usual, with its vertical axis perpendicular to the axis of spindle 6 (see Fig. 4).

A slide 10 is mounted to move on support 2 in a direction perpendicular to the axis of spindle 6 and parallel with the face of the type, said slide being provided with jaws 11—11' having projections 11—11' adapted to grasp the mold or matrix 12. A nut 13 or equivalent part formed integral with the slide 10 engages the threaded portion 14 of a spindle 15, which is journaled in support 2 by means of a bushing 32. This spindle 15 is provided at one end with a milled head 16 having graduations thereon to show the true position of the spindle corresponding with a given position of the matrix or mold 12, so that by manipulating said head 16, the

mold or matrix 12 may be shifted into proper position to bring the lower edge of the type character the desired distance from the lower edge of the type block. The screw 5 thread of spindle 15 preferably has a pitch of one millimeter, and the head of said spindle is graduated in two-hundredths of a millimeter.

- For the purpose of locking the parts of 10 the device in the desired position, the bolt 4 connecting support 2 with bracket 1 is provided at its rear end with a nut 17 which may be manipulated to clamp the bolt head 3 against the support 2 and, hence, the latter 15 against the bracket 1. The support 2 is also provided with a bolt 18 passing through a slot 31 in slide 10 and having a nut 19 adapted to clamp said slide 10 in the required position on support 2.
- 20 The device is provided with suitable means for holding the mold or matrix 12 in required position. In the construction illustrated, a known arrangement is shown comprising a stem 20 adapted to engage slots 25 provided on the rear face of the matrix 12 to clamp it against the projections 11' on jaws 11, said stem being connected with a spring plunger (not shown) mounted in a drum 21 and operated by a handle 22. The pressure 30 of the spring causes the stem 20 to bear against mold 12 and to force the same against projections 11'.

The device is mounted on the casting machine in such a manner as to have the mold 35 12 located in front of the stationary block 23 in which is provided a recess 24 forming the mold for the type block; said recess communicates through a port in the plate 25 with the nozzle 26 of the crucible 27 containing the molten metal.

By the described device the matrix or mold 12 may be carefully adjusted in correct position for each type character by manipulating heads 7 and 16 so as to locate the 45 character at the proper distances from the lower and side edges of the type block, these edges being defined by the stationary part 23. The indications shown by the 50 graduations on the vernier scales, and defining the true position of the matrix, may be read and recorded so that when it is desired to reproduce the same character, the heads 7 and 16 may be easily turned to the 55 required position for the true adjustment of the matrix 12 without again necessitating long and careful manipulations.

What I claim is:—

1. In a type casting machine, a part adapted to be mounted on the machine in front of the nozzle for the molten metal, a support arranged on said part to move in a direction parallel with the character face, a member mounted on said support to move in a direction parallel with the character face and perpendicular to the first named direction, means for clamping the type matrix on said member, means for shifting said support and member and means adapted to give a reading of the position of the matrix with regard to stationary parts of the machine. 60 65 70

2. In a type casting machine, a part adapted to be mounted on the machine in front of the nozzle for the molten metal, a support mounted on said part to move in a direction parallel with the character face, means for locking said support in position on said part, a member mounted on said support to move in a direction parallel with the character face and perpendicular to the first named direction, means for locking 75 said member in position on said support, means for clamping the type matrix on said member, means for shifting said support and member, and means adapted to give a reading of the position of the matrix with regard to stationary parts of the machine. 80 85 90

3. In a type casting machine, a part adapted to be mounted on the machine in front of the nozzle for the molten metal, a support mounted on said part to move in a direction parallel with the character face, a screwthreaded spindle provided in said part and a coöperating nut integral with said support for shifting the support, means for giving a reading of the position of said support, means for locking said support in the required position, a member mounted on said support to move in a direction parallel with the character face and perpendicular to the first named direction, a screwthreaded spindle pivoted on said support and a coöperating nut integral with said member for shifting the latter, means for giving a reading of the position of said member, means for locking said member in required position and means for clamping the type matrix on said member. 95 100 105

Signed at Turin, Italy, this 3d day of Dec., 1919.

ANGELO ALBÉ.
